UNITED STATES PATENT OFFICE.

EARBY H. McCLELLAND, OF TUCSON, ARIZONA.

GAGE-COCK.

1,247,851.

Specification of Letters Patent. Patented Nov. 27, 1917.

Application filed June 12, 1916. Serial No. 103,259.

To all whom it may concern:

Be it known that I, EARBY H. McCLELLAND, a citizen of the United States, residing at Tucson, in the county of Pima and 5 State of Arizona, have invented new and useful Improvements in Gage-Cocks, of which the following is a specification.

This invention relates to a gage cock for boilers and is particularly adaptable for use 10 upon locomotives.

It is an object of this invention to provide a gage cock having a valve adapted to be closed by means of an adjustable member acting in coöperation with the internal pressure 15 of the boiler to properly seat the valve upon its seat.

Another object is to provide simple and effective means for insuring that the conduit leading from the valve to the spigot may be 20 readily cleaned and the slime therein allowed to be removed in a semi-automatic manner.

Another object is to provide a gage cock construction in which the valve therein is not liable to stick either by the presence of foreign material deposited within the valve conduit and around the valve stem or the effect 25 due to the expansion of the parts by heat.

Another object is to provide simple means 30 whereby the valve and its seat may be ground to fit without removing any of the parts from the device or dismantling it from the boiler.

It is a further object to provide a gage 35 cock which is simple in construction and is not liable to leak.

Other objects will appear hereinafter.

The invention is illustrated in the accompanying drawings in which:

40 Figure 1 is a view in side elevation showing the gage cock as mounted upon a boiler which is shown in a fragmentary manner.

Fig. 2 is a view in longitudinal vertical section as seen on a plane similar to that of 45 Fig. 1.

Fig. 3 is a view in transverse vertical section as seen on the line 3—3 of Fig. 1 and looking in the direction of the arrow, said view particularly illustrating the disposition 50 of the cleaning vanes upon the valve stem.

Fig. 4 is a view in transverse vertical section as seen on the line 4—4 of Fig. 1.

Referring to the drawings more particularly, 10 indicates a fragmentary portion of a boiler head which is provided with a threaded opening 11 within which a threaded end 12 of a gage cock casing 13 is secured. The casing 13 extends horizontally from the boiler head and is composed of a central cylindrical body portion 14 through which a bore 15 extends. An enlarged spherical portion 16 is formed approximately mid-way the length of the cylindrical member and has an enlarged chamber 17 within it, said chamber being in communication with a spigot 65 or nipple 18 which extends vertically and downwardly and is formed with a bore 19 in communication with the chamber 17 which in turn communicates directly with the central bore 15 hereinbefore described. A hexagonal enlargement 20 is formed upon the cylindrical portion at a convenient point adjacent the boiler head, said portion being provided to facilitate in mounting the device within its threaded opening 11. The outermost end of the cylindrical body member is formed with a thread 21 which is engaged by a packing cap 22 adapted to force a packing member 23 within a packing gland 24 formed as a counterbore within the end of 80 the casing member and in communication with the central opening 17.

The end of the cylindrical casing which projects within the boiler head is formed with a conical valve seat 25 which is substantially a continuation of the wall of the central opening 15. The valve seat 25 is provided for the reception of a conical valve member 26 which is adapted to normally seat thereupon and is formed integral with a cylindrical stem 27 which extends through the opening 15 and is of a diameter slightly less than said opening. The portion of the stem extending from within the enlargement 17 and outwardly is of a diameter less than 95 that of the portion 27 and is indicated by the numeral 28. A knurled nut 29 is secured upon the outer end of the reduced portion 28 and adapted to rotate the entire stem within the sleeve 30 which extends through 100

the stuffing member 23 and into threaded engagement with the portion 31 of the central opening 15. The inner terminating end of the sleeve 30 is adapted to abut against the 5 shoulder formed by the enlarged portion of the stem 27. It will be here noted that a space 32 is provided between the knurled nut and a handle grip 23 formed integral with the outer end of the sleeve 30 for a 10 purpose which will be hereafter disclosed. A series of vanes 34 extend longitudinally of the stem portion 27 and terminate a short distance back of the valve member 26. These 15 vane members are of a diameter slightly less than that of the inside diameter of the opening 15 and are here shown as three in number.

In the operation of this gage cock when it is desired to test the boiler in order to determine the water level therein, the hand grip 23 is rotated in a direction to advance the sleeve 30 through the packing box and against the shoulder formed integral with the valve stem 27. This action will force 20 the valve member 26 from its seat and allow the water to pass between the vanes 34 and along the opening 15 to the nipple 18 where it will be drained off. In the event that the valve sticks, the sleeve 30 may be relieved 25 from the shoulder on the valve stem and the knurled nut given a blow with a suitable tool. This will allow the stem to be advanced a distance provided by the space 32 previously described. In case the opening 30 35 15 is obstructed with a foreign deposit, the knurled nut is twirled between the thumb and forefinger and the valve stem thus rotated. This action causes the vanes 34 to cut the deposit and allow the water to enter 40 the opening 15 and subsequently pass therethrough to the opening 19 in the nipple 18. In this manner slime or other deposit may be readily removed without dismantling the gage.

45 One disadvantage of gage cocks in common use is that their valves do not seat properly after short usage and consequently cause the device to leak until the valves are reground. In this device the valves may be 50 ground without removing any part of the gage cock by means of the thumb nut 29 which is rotated and in turn causes the valve member 26 to grind its own seat upon the conical seat portion 25, the lost motion as 55 indicated at 32 making it possible for the pressure within the boiler to force the valve member against its seat during the grinding operation.

60 It will thus be seen that I have provided a gage cock which may be readily mounted upon the boiler in its operative position and will operate effectively without danger of the valve member sticking upon its seat in a

fixed manner as well as to provide means for 65 cleaning the slime from the device and grinding a valve seat without dismantling the gage.

I claim:

1. In a gage cock, the combination with a boiler, of a gage cock casing secured therein, 70 a longitudinally extending bore formed through said casing and in communication with the boiler, a conical valve seat formed at the termination of said bore and in communication therewith, a draw-off member in 75 communication with said bore, a conical valve member adapted to seat upon said conical valve seat, a valve stem of a differential diameter formed integral with said valve member, and forming a passage with 80 said bore leading from said valve member to said draw-off member, a series of radially disposed cleaning vanes formed upon the valve stem and adjacent the conical valve member, a threaded valve actuating sleeve 85 mounted within the casing and adapted to act against the shoulder formed on the valve stem at the point where the stem is reduced in diameter, a packing member detachably mounted upon the outer end of the casing 90 and adapted to incase the sleeve, and means whereby the conical valve member may be rotated and reciprocated independent of the movement of the valve actuating sleeve.

2. In a gage cock, the combination with a 95 boiler, of a gage cock casing secured therein, a longitudinally extending bore formed through said casing and in communication with the boiler, a conical valve seat formed at the termination of said bore and in communication therewith, a draw-off member in 100 communication with said bore, a conical valve member adapted to seat upon said conical valve seat, a valve stem of a differential diameter formed integral with said 105 valve member and forming a passage with said bore leading from said valve member to said draw-off member, a series of radially disposed cleaning vanes formed upon the valve stem and adjacent the conical valve 110 member, a threaded valve actuating sleeve mounted within the casing and adapted to act against the shoulder formed on the valve stem at the point where the stem is reduced in diameter, and means whereby the conical valve member may be rotated and reciprocated 115 independent of the movement of the valve actuating sleeve.

3. In a gage cock, the combination with a 120 boiler, of a gage cock casing secured therein, a longitudinally extending bore formed through said casing and in communication with the boiler, a conical valve seat formed at the termination of said bore and in communication therewith, a draw-off member in 125 communication with said bore, a conical

valve member adapted to seat upon said conical valve seat, a valve stem of a differential diameter formed integral with said valve member and forming a passage with 5 said bore leading from said valve member to said draw-off member, a threaded valve actuating sleeve mounted within the casing and adapted to act against the shoulder

formed on the valve stem at the point where the stem is reduced in diameter, and means 10 whereby the conical valve member may be rotated and reciprocated independent of the movement of the valve actuating sleeve.

In testimony whereof I have signed my name to this specification.

EARBY H. McCLELLAND.
